Patented Feb. 25, 1958

182,165

COMBINED LEVEL AND MEASURING TAPE CASE

Joseph Caruso, Jersey City, N. J., assignor to Keuffel & Esser Company, Hoboken, N. J., a corporation of New Jersey

Application August 30, 1956, Serial No. 42,792

Term of patent 14 years

(Cl. D52—1)

Fig. II

Fig. I

Fig. III

Fig. V

Fig. IV

Fig. VI

Fig. 1 is a front elevational view of a combined level and measuring tape case showing my new design;

Fig. 2 is an end elevational view thereof as seen from the left of Fig. 1;

Fig. 3 is an end elevational view as seen from the right of Fig. 1;

Fig. 4 is a rear elevational view;

Fig. 5 is a top plan view; and

Fig. 6 is a bottom plan view thereof.

I claim:

The ornamental design for a combined level and measuring tape case, as shown.
